UNITED STATES PATENT OFFICE.

CHARLES F. DAUSMANN, OF GLENDALE, NEW YORK.

CYLINDER-GRINDING MACHINE.

Application filed June 8, 1923. Serial No. 644,109.

This invention relates to grinding machines and in particular to machines of this type which are employed for the purpose of grinding copper printing cylinders such as are used in the art of intaglio printing, as for instance in the production of photo-gravures.

More particularly, my present application concerns certain important practical improvements in the machine disclosed in Letters Patent No. 1,303,861, granted to me on May 20, 1919. In the patented machine, I provide means for rotating the copper cylinder and for moving a grinding stone longitudinally upon the surface of the cylinder and at the same time, rotating the stone. It was found that due to the continuous rotation of the stone in one direction, only that part of the stone at one side of its axis of rotation which moved in a direction opposite the direction of rotation of the surface of the cylinder performed the grinding function. This resulted in an uneven wear of the stone, and also rendered it impossible to grind the surface of the cylinder at both of its ends.

It is the primary object and purpose of my present improvements to remedy the above noted objections and to provide means for imparting to the grinding stone a combined reciprocatory and oscillating movement as the stone is moved longitudinally upon the surface of the cylinder. By the oscillatory movement of the stone as distinguished from its continuous rotation in one direction, I obtain a uniform grinding or polishing action of the stone upon the surface of the cylinder at each side of the axis of the oscillatory movement of the stone. Thus, though the cylinder is continuously rotating in one direction, it will be apparent that the surface of the cylinder can be properly ground throughout its entire length.

It is also an important feature of my new machine to provide improved means for mounting the grinding stone and adjustably regulating its bearing pressure upon the surface of the cylinder.

As a further item of improvement upon my prior invention I have provided a simple and positively actuating means for automatically controlling and reversing the movement of the sliding carriage upon which the grinding stone is mounted.

With the above and other objects in view,

the invention consists in the improved grinding machine and in the form, construction and relative arrangement of its several parts as will be hereinafter more fully described, illustrated in the accompanying drawings and subsequently incorporated in the subjoined claims.

In the drawings wherein I have illustrated one simple and practical embodiment of the new machine and in which similar reference characters designate corresponding parts throughout the several views,

Figure 1 is a side elevation of a grinding machine constructed in accordance with my invention;

Figure 2 is an end elevation thereof;

Figure 3 is an elevation of the opposite end of the machine, certain parts being in section;

Figure 4 is a fragmentary elevation partly in section illustrating the mounting and operating means for the reciprocating carrying frame of the grinding stone;

Figure 5 is a detail transverse section taken on the line 5—5 of Figure 1;

Figure 6 is a sectional view taken on the line 6—6 of Figure 5;

Figure 7 is a detail transverse section taken on the line 7—7 of Figure 1;

Figure 8 is a detail vertical section taken on the line 8—8 of Figure 3;

Figure 9 is a detail elevation partly in section of the automatic reversing means for the stone carriage;

Fig. 10 is a plan view, the different positions assumed by the grinding stone being illustrated in broken lines.

Referring in detail to the drawings in which I have disclosed one practical construction of the machine, the several operating parts are mounted upon a suitably supported frame structure 5, said frame structure at its upper end being provided at opposite sides thereof with longitudinally extending guide rails 6 for the bed plate 7 of a slidably mounted carriage. A transversely adjustable tool support 8 is centrally mounted on the bed plate 7 for a purpose which will be later referred to.

Upon opposite ends of the bed plate 7, the standards or uprights 9 are suitably fixed at their lower ends. These standards at their upper ends are provided with guide-ways 10 for a reciprocating frame 11. The side bars of this frame which are engaged in the guide-ways terminate at one of their

ends in the yokes 12 which receive the opposite ends of an eccentric 13 having the shaft extensions 14 at its opposite ends which are journaled in bearing arms 15 fixed to the standards 9. In the other end of the frame 11 the arm 17 formed upon the plate 16 is pivotally mounted, said arm having a lug 18 carrying an adjustable stop screw 19 adapted to engage the underside of the frame 11 and limit the pivotal or swinging movement of the plate 16 in one direction with respect to said frame. The holder 20 for the grinding stone 21 is journaled in the plate 16. This holder is provided upon one side with a lug 22 to which one end of a link 23 is pivotally connected, the other end of said link being pivoted to an arm 23' which is fixed to a tie rod 24 connecting the uprights or standards 9. This link 23 has a lateral or rocking or tilting action on its pivotal connection with arm 23'.

In order to regulate the bearing pressure of the stone upon the surface of the cylinder being ground, I provide a threaded rod or stem 25 suitably fixed at its lower end to the plate 16 and extending outwardly therefrom, said rod being adapted to receive one or more weights 26 and a nut 27 which may be adjusted into clamping engagement upon the uppermost weight.

One end of a flexible element 27' is connected to the upper end of the rod 25, the other end of this flexible element being attached to a drum 28 fixed upon a shaft 29 journaled in suitable bearings 30 at its ends which are mounted on the upper ends of the standards 9. To one end of this shaft a worm gear 31 is fixed and is engaged by a worm 32 on the shaft 33 mounted in the bearing 34 and actuated by the hand wheel 35. When it is desired to lift the stone to an inoperative position, it is only necessary to rotate the hand wheel 35 in the proper direction to thereby wind the flexible element 27' upon the drum 28. Upon unwinding the element 27' from said drum, the stone will be lowered into contact upon the surface of the cylinder, and the pressure of the stone upon said surface may be adjusted as desired by the operation of the set screw 19.

To one side of the frame 5 at one of its ends the bearing support 36 for one end of the cylinder shaft is rigidly bolted. To the opposite end of the frame a casting 37 is secured, said casting having a transversely extending arm 38 upon one side of which spaced bearing surfaces 39 are formed for the lower end of the standard or support 40 in the upper end of which the other end of the cylinder shaft is adapted to be mounted. The casting arm 38 is provided with threaded openings adapted to receive the clamping bolts 41 and said support 40 is adjusted upon the bearing surfaces 39 by

means of the screws 42 arranged upon the arm 38 and contacting with the opposite vertical edges of said support. By adjusting these screws, the support may be moved longitudinally upon the arm 38 until the bolt openings thereof are in line with the threaded openings in said arm so that the bolts 41 may be threaded home to securely clamp and fix the support in position. The upper end of each of the supports 36 and 40 is provided with a half bearing, and after the shaft ends of the cylinder 43 have been engaged therein, the other halves 44 of the bearings are arranged over the shafts and securely bolted to the upper ends of said supports.

The main drive shaft 45 extending the entire length of the machine is suitably mounted in the lower part of the frame structure, said shaft at one end of the frame being also supported by the bearing 46. Between this bearing and the frame end a belt wheel 47 is fixed upon the drive shaft and is connected by the belt 48 with a relatively small wheel 49 fixed upon the shaft 50 journaled in the bearing arm 52 fixed to one side of the frame 5. A gear 53 fixed upon the shaft 50 is engaged with a relatively large gear 54 which is secured to one end of the shaft of the printing cylinder 43 whereby said cylinder is rotated.

In the upper portion of the frame structure 5 and centrally thereof the longitudinally extending worm shaft 55 is rotatably mounted, one end of this shaft having a gear 56 fixed thereto adapted for engagement by the pinion 57 secured upon a shaft 58 which is journaled in one of the arms of an angular lever 59 fulcrumed for rocking movement upon the main shaft 45. A second larger gear wheel 60 is also fixed upon the shaft 58 and is in mesh with a pinion 61 secured on the main shaft 45. The other arm of the lever 59 is provided with a suitable operating handle 62 and has a slot 63 formed therein to receive the stop pin 64 fixed in the end of the frame and which limits the shifting movement of said angular lever to engage the pinion 57 with the gear 56 or to disengage the pinion from said gear.

Upon one end of the carriage bed 7 a half nut 65 is vertically adjustable in a suitable guide 66. Preferably, this half nut is adjusted by the eccentric device shown in Figures 5 and 6 of the drawings. Thus the shank portion 67 of the nut which is movable in the guide 66 is provided with an opening to receive the eccentric 68 of the shaft 69 which is fixed to the operating lever 70. When the operating lever is in the full line position as shown in Figure 5 of the drawings, the threads of the half nut 65 are engaged with the threads of the worm shaft 55. By throwing this lever over to the dotted line position, the eccentric 68 acts to move

the half nut upwardly out of engagement with the worm shaft to an inoperative position. The purpose of this means for disconnecting the carriage from the worm shaft 5 or screw 55 will presently appear.

To one side of the frame 5 a longitudinally extending rack 71 is suitably secured, the teeth of said rack being engaged by a pinion 72 fixed upon the shaft of the hand wheel 73 which is journaled in a supporting bracket 74 fixed to the bed plate 7 of the carriage.

Along one side of the frame 5 the longitudinally disposed shaft 75 is journaled in suitable bearings 76 and a beveled gear 77 journaled in an arm 78 on the carriage bed is keyed or splined for sliding movement along this shaft. A vertically disposed shaft 79 is mounted in spaced bearings 80 on one of the carriage standards or uprights 9 and a beveled gear 81 on the lower end of this shaft meshes with the gear 77. The beveled gear 82 on the upper end of the shaft 79 is engaged with a beveled gear 83 which is fixed to one of the shaft extensions 14 of the eccentric 13.

Upon one end of the shaft 75 the gear wheel 84 is fixed and meshes with a similar gear 85 mounted upon a stud shaft fixed to the frame, said latter gear being engaged with a pinion 86 secured upon the main drive shaft 45.

For the purpose of automatically controlling the movement of the carriage and reversing its traveling movement when the grinding stone reaches the end of the cylinder 43, I provide the mechanism illustrated in Figure 9 of the drawings. One end of the worm shaft or screw 55 is journaled in a bracket arm 87 fixed to the end of the machine frame and upon this shaft end the opposed spaced beveled gears 88 are loosely mounted. A double clutch member 89 is keyed upon the shaft for sliding movement between the gears 88, the ends of said member and the gears being provided with the usual frictionally coacting clutch surfaces so that when the member 89 is shifted in one direction, one of said gears is locked to the shaft and when shifted in the opposite direction the first gear is released and the other gear locked to the shaft. The gears 88 are engaged at their lower sides by a beveled driving pinion 90 fixed upon the upper end of a vertically disposed shaft 91 mounted in a suitable bearing formed on the bracket arm 87. To the lower end of this shaft the beveled pinion 92 is fixed and meshes with a similar beveled pinion 93 fixed upon the end of the drive shaft 45.

The clutch member 89 is shifted by a yoke 94 which is fixed to the upper end of a lever 95 fulcrumed intermediate of its ends as at 96 upon the bracket 97 fixed to the machine frame. The lower end of this lever is pro-

vided with a head having oppositely beveled faces 98 at its lower side with which similarly beveled faces 99 on the upper end of a locking member 100 are adapted to coact. This member is mounted for vertical movement under the action of a spring 101 in a guide cavity formed in the end of an arm 102 which is integral with the bearing bracket 103 fixed to the end of the machine frame and in which the end of the drive shaft 45 is journaled.

The lever 95 is actuated by a longitudinally movable rod 104 which is pivotally connected at one of its ends as at 105 to the upper end of said lever. This rod extends substantially the full length of the frame and is supported in suitable guide lugs 106 fixed to one side of the frame. One of these lugs is provided with an adjustable set screw 107 adapted to engage the shiftable rod and retain the lever 95 in a neutral position, as seen in Figure 9.

The carriage bed 7 is provided adjacent its opposite ends with the downwardly projecting apertured lugs 108 through which the rod 104 loosely extends. Upon this rod in spaced relation to each end thereof the fixed and loose collars 109 and 110 respectively, are disposed and the ends of the coil spring 111 surrounding the rod 104 are attached to said collars. These springs serve as cushioning means when the lugs 108 on the carriage bed strike the loose collars 110 so that said springs are compressed in the shifting movements of the rod 104.

Before grinding the cylinder, the roughened surface thereof is first turned down by a suitable cutting tool mounted in the tool rest 8. During such operation the clutch member 89 is held in a neutral position by fixing the rod 104 against movement by means of the set screw 107 and the lever 59 is actuated to disengage the pinion 57 from the gear 56. The hand wheel 73 may now be turned so that the pinion 72 will move along the rack 71 and thus shift the carriage as desired to properly position the cutting tool with respect to the revolving cylinder. It is of course understood that during this manual operation, the nut 65 is in an inoperative position, having been lifted from the worm or lead screw by the operation of the eccentric 68. At any time, however, the nut may be engaged with said lead screw and the lever 59 actuated to engage pinion 57 with gear 56 so that the carriage will be automatically moved after the cutting tool has been initially positioned and turn down the surface of the cylinder throughout its length.

When the cylinder is to be ground the bar 104 is released by loosening the set screw 107. When the carriage is at one end of its travel with one of the stops 108 engaged against one of the collars 110, the lever 95 will be in an angular position with respect

to that seen in Figure 9 and the clutch member 89 will be in driving engagement with one of the gears 88. One of the beveled faces 99 of the locking member 100 coacting with one of the beveled faces 98 on the lower end of the lever effectually holds the lever in such position and maintains the driving connection. Thus rotation will be transmitted from the drive shaft 45 through 10 the vertical shaft 91 and the connecting gearing to one of the gears 88 to rotate the worm or lead screw 55 in one direction and cause the longitudinal travel of the carriage. In this traveling movement of the carriage the 15 shaft 75 is rotated and through the vertical shaft 79 and the connecting gearing, the eccentric 13 is actuated so that the frame 11 will be reciprocated to shift the grinding stone 21 across the surface of the printing 20 cylinder in a direction at right angles to its axis. At the same time, during this reciprocating movement, the link 23 imparts an oscillatory motion to the stone 21 so that in the reciprocating movement of the stone in 25 one direction, the face of the stone at one side of its axis has a grinding action upon the surface of the cylinder, and during the reciprocating movement in the opposite direction the surface of the stone at the other 30 side of its axis will grind the surface of the cylinder. As seen in Figure 10 of the drawings, A indicates the position assumed by the stone holder at the end of its outward reciprocating motion, and B indicates the 35 position of the stone holder at the end of its inward movement. As the axis of the stone is thus shifted in a straight line maintained by frame 11 and guideways 10, it is oscillated about its own axis at 25 by connection of the lug 22 to link 23. The pivoting of this lug to link 23 would tend to cause the center of the stone to swing in an arc about said pivot, but as this is impossible because of the mounting of the stone carriage 40 the pivot itself moves slightly toward and from the line of reciprocation of the stone as permitted by lateral rocking of link 23 on its pivot on arm 23'. Thus, there will be uniform wear upon the stone and the surface of the cylinder will be uniformly ground down to its extreme ends. When the carriage reaches the limit of its movement in one direction and one of the stops 108 engages the collar 110, the rod 104 is shifted 45 to reverse the angular position of the lever 95 and disengage the clutch member 89 from the one gear 88 and engage said member with the other gear 88 so that the rotation of the worm or lead screw 55 will be reversed, 50 thus automatically reversing the direction of travel of the carriage.

After the grinding operation has been completed, the wheel 35 is turned to rotate the shaft 29 and wind the flexible connection 27' on the drum 28, thus lifting the

grinding stone from the cylinder so that the latter can be conveniently removed.

From the foregoing description considered in connection with the accompanying drawings, it will be seen that I have produced a 70 grinding machine for copper printing cylinders whereby the cylinder may be very quickly provided with a perfectly smooth and highly polished surface to receive the etching. In the accompanying description, I 75 have referred with some particularity to the relative mounting and arrangement of the several parts of the machine as in practice, the illustrated embodiment of the invention has been found highly satisfactory. However, it will be manifest that the purpose of my present improvements might be attained in other alternative machine structures, and I therefore reserve the privilege of resorting to all such legitimate changes in the form, 80 proportion and relative arrangement of the several parts as may be fairly embodied within the spirit and scope of the invention as claimed.

I claim:

1. In a grinding machine for printing cylinders, a carriage, a frame mounted in the carriage for rectilinear reciprocating movement in a direction at right angles to the movement of the carriage, an oscillatory grinding stone mounted in said frame and adapted for movement across the surface of the cylinder at right angles to the cylinder axis in the reciprocating movement of said frame, means for reciprocating said frame, and means mounted in the carriage and connected with said stone to cause an oscillating motion of the latter about its own center due solely to the reciprocation thereof.

2. In a grinding machine for printing cylinders, a carriage, a frame mounted in the carriage for rectilinear reciprocating movement in a direction at right angles to the movement of the carriage, an oscillatory grinding stone mounted in said frame and adapted for movement across the surface of the cylinder at right angles to the cylinder axis in the reciprocating movement of said frame, means for reciprocating said frame, and a link member mounted at one of its ends in said carriage and having a pivotal connection at its other end with said stone whereby an oscillating motion about its own center is imparted to the stone due solely to the reciprocation thereof.

3. In a grinding machine for printing cylinders, means for rotatably supporting a cylinder, a carriage mounted to travel longitudinally of the cylinder and operating means therefor, a frame mounted for rectilinear reciprocating movement in said carriage at right angles to the line of travel thereof, a grinding stone, a holder for said grinding stone pivotally mounted in said frame for vertical swinging movement and

for oscillation about a fixed central axis relative to said frame, and means mounted in said carriage and connected with said stone holder for causing the reciprocating movements thereto to impart an oscillatory motion to said holder.

4. In a grinding machine for printing cylinders, cylinder rotating means, a frame mounted for rectilinear reciprocating movement, a grinding stone carried by said frame and mounted to swing vertically with respect thereto, said stone being arranged for tangential contact upon the periphery of the cylinder, means for reciprocating said frame and stone, and a member having a fixed pivot at one end and pivotally connected at its other end with the stone to impart an oscillating movement to the stone about a central axis during its reciprocating movements.

20 5. In a grinding machine for printing

cylinders, a carriage, means for mounting a grinding stone upon said carriage for oscillatory motion in a horizontal plane about a central axis and for transverse reciprocating motion at right angles to the axis of the cylinder and in contact with the surface thereof during the movement of the carriage, means for moving the carriage and stone longitudinally of the cylinder, power operated means on the carriage for reciprocating the stone, and additional means connecting the stone with the carriage to cause an oscillatory motion of the stone about its own center by the reciprocating movements thereof.

25 30 35 In testimony that I claim the foregoing as my invention, I have signed my name hereunder.

CHARLES F. DAUSMANN.
